UNITED STATES PATENT OFFICE.

EUSÈBE ALEXIS MARTEL AND LÉONIDAS JOSEPH MERCIER, OF ST. ISIDORE D'AUCKLAND, QUEBEC, CANADA.

RAILWAY-CROSSING GATE.

1,355,492.

Specification of Letters Patent.

Patented Oct. 12, 1920.

Application filed March 20, 1920. Serial No. 367,317.

To all whom it may concern:

Be it known that we, EUSÈBE A. MARTEL and LÉONIDAS J. MERCIER, both subjects of the King of Great Britain, residing at St. 5 Isidore d'Auckland, Province of Quebec, Canada, have invented certain new and useful Improvements in Railway-Crossing Gates; and we do hereby declare that the following is a full, clear, and exact description of the invention, such as will enable others skilled in the art to which it 10 pertains to make and use the same.

The present invention relates to a railway crossing gate for grade crossings between 15 railways and highways, and, further, a gate of the type that is adapted to be automatically operated by the approaching train to close the gate and to open the same after leaving the crossing, the said automatic operation being accomplished by means of co- 20 acting connections.

The principal object of the invention is to produce a crossing gate which shall be infallibly operated by the train so as to be opened 25 or closed which shall dispense with electrical, pneumatic, and other indirect means for closing and opening the gates, which latter are liable to frequent derangement and thus to fail at critical times and to cause the 30 power of the locomotive to act directly upon the gate without the interposition of any other power to open and close the same.

The invention further consists in the special arrangement of shafts and pulleys by 35 which the gates are connected together, so as to be raised and lowered simultaneously in opposite directions.

The invention provides for an auxiliary gate, which is adapted to be lowered to give 40 warning of the approach of the train prior to the lowering of the safety gates.

The invention consists, furthermore, in the constructions and combinations of parts hereinafter described, and more particularly 45 pointed out in the claims.

In the drawings accompanying this specification, we have illustrated our invention as applied to a single track railroad, but it is understood that the same principle may be 50 applied to a double track system, together with the specific and most approved designs of the details by which the parts coact with one another, and herein:

Figure 1 is a perspective view of a road-

way crossing on a single track road, provided with gates according to our invention;

Fig. 2 is a plan view of the same, with the locomotive schematically shown;

Fig. 3 is a side elevational view of that portion of the device against which the pilot 60 of the locomotive engages;

Figs. 4, 5 and 6 are detail elevational views of the operating levers, illustrating the various positions assumed by the same when engaged by the locomotive pilot to 65 actuate the auxiliary signal gate;

Fig. 7 is a detail view of the signal gate and part of the mechanism therefor;

Fig. 8 is a detail view of the lever for actuating the signal gate;

Fig. 9 is a section on line 9—9 of Fig. 8;

Fig. 10 is a detail section with a portion of the plate broken away;

Fig. 11 is a section on line 11—11 of Fig. 10;

Figs. 12 and 13 are plan views of the levers;

Fig. 14 is a detail view of the gate operating lever;

Fig. 15 is a section on line 15—15 of Fig. 14;

Fig. 16 is a detail section of one of the cable pulleys mounted on the operating shaft;

Fig. 17 is a perspective view of a post with the tackles and cables;

Fig. 18 is an end elevational view of the gate supporting standards and operative mechanism for the gates; and,

Fig. 19 is a fragmental detail elevation of the gate and standard.

Referring to the figures by numerals of reference, 1 and 2 indicate the gates proper which are preferably formed of bars which converge at their outer ends. The inner 95 ends of the gates are pivotally secured to the standard housings 3 and 4 by means of the shafts 5 and 6 mounted in the upper ends of the side bars 7 and 8 of said standards.

A shaft 9 connects standards 3 and 4 and extends beneath the track 10. Secured to shaft 9 are the pulleys 11 and 12 which operate in the base of the housings 3 and 4. And likewise pulleys 13 and 14 are mounted 105 on the upper shafts 5 and 6.

A standard housing 17 is arranged to one side of the highway crossing 16 and opposite

to standard housing 4, but is of greater height than the housing 3 and 4. Likewise mounted in the upper end of said housing 17 on shaft 18 is a signal arm or semaphore 19, which carries a plurality of ropes 20 or some color designation. A pulley 21 is mounted on shaft 22 at the base of the standard housing 17 and a cable 23 is connected at one end to a trip lever 24 mounted in the journal casing 25 at a relatively great distance from a crossing. This cable 23 is trained over the tackles 26 having link connection 27 to the posts 28 and over the pulley 21 of standard casing 17; the cable 23 10 is then passed back over the upper surface of the tackles 26 and the opposite end is secured to the trip lever 29, pivotally mounted in the journal casing 30. Springs 37 and 37' are secured at one end to housing casings 25 and 30 and at the lower ends of trip levers 24 and 29. These levers 24 and 29 20 are formed with cut away portions 51 and 52 on one side which engage with lugs 53 and 54 on shaft 55 and 56.

25 Therefore, a locomotive after passing the gates strikes these levers 24 and 29 the same will be forced in a direction opposite to and away from the gates without revolving or changing position of shafts 55 and 56 or 30 lugs 53 and 54.

Levers 24 and 29 are then returned to a vertical position by the tension of springs 37 and 37'.

By this means it will be seen that the signal gate 19 will not be needlessly operated after train has passed the crossing.

The trip levers 24 and 29 are spaced apart at such distance, so that upon the locomotive pilot engaging the trip lever 24, the signal arm 19 will be actuated, to dispose the same in the position indicated in Fig. 7, that is, across the roadway 16. When the locomotive has passed lever 24, it will then engage lever 29 and such engagement will actuate cable 23 and elevate the signal 19 to its normal vertical position.

The mechanism for actuating gates 1 and 2 will now be described. A trip lever 31 is mounted in the journal casing 31 and a cable 32 50 is trained at one end over the pulley 11 in the base of the housing 3. This cable 32 is likewise trained over the tackles 33, attached to the posts 34 and at its opposite end, is wound around the pulley 35 on shaft 36, on which the trip lever 31 is mounted. A spring 37 is secured at one end to the housing plate 38 at the lower end of the trip lever 31.

When the pilot of the locomotive engages 60 lever 31, the latter is rocked on its pivotal connection 36 and resultantly cable 32 is actuated, which revolves pulley 11. In this manner, cable 39, trained over pulleys 13 and 11, is moved, and shaft 9 is likewise 65 actuated to move pulley 12. A cable 40 is

trained over pulleys 12 and 14 of the standard casing 4, and when trip lever 31 is actuated as stated, the gates 1 and 2 are lowered.

A trip lever 41 is mounted on shaft 52 in 70 the journal casing 43, located some distance beyond the crossing 16, and a pulley 44 is mounted on shaft 42 and a cable 45 is trained at one end over pulley 44 and at the opposite end over pulley 12 on shaft 9 75 in the standard casing 4.

When the pilot of the locomotive strikes the lever 41 the pulley 44 is revolved, which actuates the cable 45 and in turn pulley 12. In this manner, the cables 39 and 40 in the 80 casings 3 and 4 are actuated to cause the lowering of the gates 1 and 2.

Levers 31 and 41 are formed with enlarged weighted base portions 46 and are formed with cut away portions 47 and 48 at 85 each side which engage the lugs 49 and 50 on shaft 42.

By the provision of the cut away portions 47 and 48 with respect to the lugs 49 and 50, the impact of the pilot with the lever 90 41 is modified and the lever owing to its weighted end will resume normal vertical position. Likewise lever 31 is of the same construction and it cooperates with lever 41 in returning the gates 1 and 2 to vertical 95 position.

In this manner, we have provided a crossing gate that is directly actuated by the locomotive and which first signals at the crossing upon the approach of the train and 100 then lowers the gates. The gates are then elevated to their normal vertical position by contact of the locomotive pilot with the lever 41.

It is understood that the means of operating the signal arm is symmetrical on either side of roadway crossing but owing to the extreme difficulty of illustrating a device of this nature and so that the drawings will be easily readable we have shown 110 only one side of the operation in our views as Fig. 1.

Having thus described our invention, what we claim is:

1. A railway gate pivotally supported 115 adjacent its lower end, a support mounted adjacent said gate, a shaft journaled for rotation in said support, a pulley keyed to said shaft, a lever fulcrumed on the shaft, said lever having a counterweight at its 120 lower end, said counterweight being cut away at opposite sides to form oppositely disposed shoulders, pins projecting from the shaft at opposite angles and disposed in the paths of said shoulders for contact therewith upon movement between said shaft and lever, cable connections between the gate and pulley, and means operated by an engine or the like for tripping said lever 125 and actuating the gate. 130

2. In an apparatus of the class described, the combination with the railway rails of a track and a gate pivotally supported adjacent to said track, a bracket mounted adjacent to the rails convenient to the gate, a shaft journaled in said bracket transversely of the rails, a pulley keyed to said shaft, a lever fulcrumed on said shaft, said lever having its lower end increased in diameter and thickness, and equal extending opposite sides of the lever constituting a counterweight, said counterweight upon opposite sides of the lever being cut out in triangular

formation and providing oppositely disposed shoulders arranged upon opposite sides of the lever, pins projecting from the shaft in opposite directions and extending in said cut out portions of the counterweight for engagement with the shoulders thereof, cable connections between the gate and pulley, and an engine operating means for tripping said lever and actuating the gate. 15
20

In witness whereof we have hereunto set our hands.

EUSÈBE ALEXIS MARTEL.

LÉONIDAS JOSEPH MERCIER.
